UNITED STATES PATENT OFFICE

HANS P. NELSON, OF GRANTWOOD, NEW JERSEY

TAPERED CENTER FOR RIDING CROPS

Application filed May 16, 1931. Serial No. 537,944.

This invention relates generally to whips and the improvements are directed to a novel form of centers or cores adapted for use in the fabrication of a riding crop or the like.

5 Primarily, the object of the present invention resides in the provision of a center of the above-mentioned character wherein an exceedingly high degree of flexibility is attained without danger of breaking or of de-

10 forming the original formation of the center.

Another object resides in the reduction of a material, such as celluloid, to a plastic form of suitable dimensions and thereafter treating the exterior surface of said form with an 15 air-tight and water-tight plastic material, thereby preserving the inherent resiliency and pliability of the celluloid.

Still another object of the invention is to provide a center or core formed from celluloid which is suitably tapered for fabrication 20 into a riding crop, said core of celluloid being susceptible of blending with various colors, as desired, thus forming a solid compact substance of great pliability and which offers 25 little if any resistance to bending in a bowed condition for a reasonable time.

As will presently appear my improved center or core is formed from relatively pliable and plastic material, wherein its residual 30 moisture is sealed within the core, thus preventing the escape of said moisture and subsequent breaking of said center due to brittleness so often occurring in centers not properly sealed from the effects of atmospheric conditions.

A further feature of the invention resides in the provision of a core or center, formed from celluloid, or the like, and having a coating or rubber-like liquid applied thereto to 40 seal the exterior surface of said center as aforesaid.

Still another aim is to provide a core or center which may be given a highly polished surface and which may be blended with colors 45 to produce variegated color effects.

With these objects in view, together with others which will appear as the description proceeds, the invention resides in the novel formation, combination, and arrangement of 50 parts, all as will be described more fully here-

inafter, illustrated in the drawing and particularly pointed out in the claims.

In said drawing:

Figure 1 is an elevation of my novel and improved tapered center for riding crops 55 or the like.

Fig. 2 is a transverse sectional view taken on the plane of the line 2—2 of Fig. 1.

Fig. 3 is a view like unto Fig. 1, but showing said center entirely encased by air-tight 60 and water-tight material.

Fig. 4 is a sectional view taken on the plane of the line 4—4 of Fig. 3.

Fig. 5 is an elevation of a riding crop embodying my novel center or core. 65

Fig. 6 is a partial elevational view, somewhat enlarged, and partly in section, to illustrate one method of securing my novel center to the handle or grip portion of a riding crop. 70

Before presenting the invention in detailed form, it is desired to point out that while my novel and improved center is illustrated and will be described in connection with its use in the fabrication of a riding crop, it is to be understood that such fabrication is merely illustrative of one of the many adaptations of my invention, as obviously said center may find use in connection with articles wherein a staff member of great 75 resiliency and pliability is a desideratum.

Referring now more in detail to the accompanying drawing, wherein like characters of reference denote similar parts throughout the several views, let 5 indicate 80 my improved center for a riding crop, or the like, and as shown in Fig. 1, said center may be given a gentle taper to better adapt the same to the use about to be described. Said center is preferably formed of celluloid, 85 which presents a high degree of plasticity and resiliency so long as its inherent elasticity is not impaired by the removal of its moisture-content due to exposure to the atmosphere. Hence, it appears that celluloid is 90 especially adapted for this particular use, provided means is provided for preventing the evaporation or escape of its moisture content. To this end I propose to coat or encase said center with a rubber-like material, 95 100

which, due to its plastic nature fails to impair the natural resiliency of the celluloid and at the same time prevents the escape of its moisture content thus retaining the flexibility of the center. As shown in Fig. 3, said coating or casing 6 covers the exterior surface of said center, including the top and bottom faces and thus the moisture content of said center is sealed from the deteriorating effects of the atmosphere. It will be appreciated that the exterior surface of the article may be highly polished, if desired, and also the celluloid forming the center may be blended with colors to produce beautiful and decorative effects.

With the center in the condition shown in Figs. 3 and 4 it is ready for fabrication into a riding crop or similar article, such as a cane, or similar staff articles.

20 The riding crop 7, shown in Fig. 5, comprises the usual handle or grip member 8, which may assume many forms in keeping with the use of a riding crop and in this particular instance a simulation of a riding boot 25 has been adopted. As shown in Fig. 6 the shank portion 9 of said handle is provided with a recess 10 for the reception of the butt-end of said center 5, suitable adhesives being applied to assure a tight joint at this point. 30 The encased center 5 is now wrapped with a covering of leather 11, which latter may be in the form of woven strips of material extending from the top of the shank 9 to the tip of said center. Said tip is then finished 35 by the application of binding material 12 which serves to secure the lash or loop 13 to said tip, as shown in Fig. 5. The juncture of the center with the shank 9 is finished by the application of an annular member 14 40 which serves to fasten a loop 15 to the article. The above description of the riding crop, with the exception of the center, of course, is more or less common in the construction of a riding crop, although variations are contemplated and may be resorted to.

45 From the foregoing it will be seen that I have provided a center possessing a high degree of resiliency and which may be bent or bowed to a startling degree without danger 50 of breaking or snapping of said center. At the same time said center readily assumes its normal position without distortion or deformation.

55 Since the center may be highly polished it may be used in many instances wherein the usual covering of leather, present in a riding crop, is not desired and in view of the protection afforded by the coating or covering of plastic material 6, its natural resiliency is not impaired over a long period of time.

60 While the present is a disclosure of the preferred embodiment of the invention, it is to be understood that the invention is not 65 limited thereto, as various changes in the

minor details of construction, proportion and arrangement of parts may be resorted to without departing from the spirit of the invention as defined in the appended claims.

70 I claim:

1. A tapered center for a riding crop composed of solid celluloid.
2. A tapered center for a riding crop composed of celluloid and having a coating of non-porous material applied thereto to seal 75 the exterior surface of said center.
3. A tapered center for a riding crop composed of celluloid and a covering of watertight plastic material applied thereto to seal the exterior surface of said center.
4. A solid tapering center serving as a center support for a riding crop comprising molten celluloid formed into a solid tapering core and having an impervious casing to prevent the escape of its inherent and residual 85 moisture therefrom.

5. A solid tapering center forming a core for a riding crop composed of plastic celluloid material encased in a coating of non-porous material to prevent the entrance of 90 moisture into said core.

95 In testimony whereof I affix my signature.
HANS P. NELSON.
